ORCHARD HEATER

William E. Nance and James B. Stone, Redlands,
Calif.

Application July 3, 1937, Serial No. 151,908

5 Claims. (Cl. 158—91)

This invention relates to outdoor heaters such as are used chiefly for protecting trees from frost and is particularly applicable to oil burning heaters.

An object of the invention is to provide an unusually efficient and smokeless heater of the type referred to for burning ordinary fuel oil.

A more specific object of the invention is to provide an attachment for installation on heaters of existing types for making such heaters more efficient, both with respect to the amount of useful heat produced and the reduction of smoke.

In co-pending application of William E. Nance, Serial No. 143,099, filed May 17th, 1937 on an Orchard heater, one of the joint inventors herein has disclosed an improvement in oil burning orchard heaters whereby existing heaters of at present widely used types can be improved by substituting for the old cover and stack an improved cover and stack. In accordance with the present invention, among other things, we provide a collar or coupling which may be inserted between the tank and cover of many existing heaters to improve the operation of the heaters. This collar or coupling is highly advantageous in that it costs less to produce than a complete cover and makes possible the use of the old cover on the old tank.

The invention will now be explained by describing in detail with reference to the drawing certain specific embodiments of the invention, it being understood that various changes can be made in the particular structure shown without departing from the invention.

In the drawing:

Fig. 1 is a side elevational view with a portion broken away of a complete orchard heater of the round tank type equipped in accordance with our invention.

Fig. 2 is a detail vertical sectional view through the lower portion of the heater shown in Fig. 1, the section being taken approximately in the line II—II of Fig. 1.

Fig. 3 is a plan view of the separable collar attachment employed in the heater of Fig. 1.

Fig. 4 is a horizontal section in the plane IV—IV of Fig. 1.

Fig. 5 is a vertical section through the collar shown in Fig. 3, the section being taken in the plane V—V of Fig. 3.

Fig. 6 is a vertical section through a square type orchard heater incorporating our invention.

Fig. 7 is a detail elevational view of the inside of one corner of the tank shown in Fig. 6 with

the separable collar positioned above the tank preliminary to attachment to the tank; and

Fig. 8 is a view similar to Fig. 7 but showing the collar inserted in place on the tank.

Referring first to Fig. 1, the heater therein disclosed comprises as its essential elements a tank 1 for containing fuel oil, a collar 2 positioned on top of the tank 1, and a cover 3 positioned on top of the collar 2, this cover having an outlet flange of reduced size which receives and supports a stack 4.

The tank 1 is of very simple construction, consisting simply of an open top, flat bottom, cylindrical receptacle, preferably of seamless or welded construction so that it will remain liquid-tight despite exposure to the weather. These tanks may be constructed in various sizes, usually being approximately 19" in diameter and substantially half as deep, the relative proportions being approximately as shown in the drawing.

The collar 2 consists of a substantially cylindrical band 7 of internal diameter at the lower end such as to fit snugly about the upper end of the tank 1. It is preferably provided with an inwardly extending circumferential bead 6 positioned slightly above the lower edge, which bead engages the upper edge of the tank 1 and limits downward movement of the collar on the tank.

The band 7 may be 4" or 5" in height or width, depending upon the dimensions of the tank with which it is to be used, and at its upper edge is of slightly smaller diameter than at the lower edge, so that the external diameter of the upper edge approximates the external diameter of the upper edge of the tank 1, so that a cover 3 adapted to fit upon the top of the tank 1 will also fit on top of the band 7. An external circumferential bead 8 may be provided a short distance below the upper end of the band 7 to limit downward movement of the collar 3 on the band.

The cover 3, as shown in the drawing, is substantially in accordance with prior practice and comprises simply an inwardly and upwardly sloping member having a flange 9 at the upper end defining an outlet opening into the stack 4. It is usually provided with an air inlet opening 10 adapted to be closed by a sliding cover 11. In the present invention this opening 10 is not employed and is maintained closed by the cover 11 except during ignition of the burner.

Referring now to Figs. 3, 4 and 5, the collar 2 has attached thereto at diametrically opposite points intermediate the lower bead 6 and the upward bead 8 a pair of inwardly and upwardly

extending pipes 12 and 13, respectively, which pipes merge into each other and into an air discharge head 14 centrally of the burner immediately below the stack 4. The head 14 is provided with a large number of relatively small air apertures 15. The outer ends of the tubes 12 and 13 communicate with the exterior through apertures provided therefor in the band 7. In operation, air is drawn into the pipes 12 and 13, being heated during its passage therethrough and discharged in numerous small jets through the apertures 15 into the burning gases within the cover 3. This air is intimately mixed with the burning gases, facilitating combustion and increasing the amount of heat produced and reducing the amount of smoke produced.

The tubes 12 and 13 may be of any desired cross-sectional shape but we have found it convenient to make these tubes of rectangular cross-section and in a tank of average size the tubes may be approximately $1\frac{1}{2}$ " in vertical cross-sectional dimension and about 3" in horizontal cross-sectional dimension.

The band 7 also has attached thereto and downwardly depending therefrom a wall member 16 which, when the collar 2 is assembled on the tank 1, constitutes a false or auxiliary wall slightly spaced inwardly from the main wall of the tank 1. The main portion of the wall member 16 may be cylindrically curved so that it fits in concentric relation with the wall of the tank 1 and extends substantially from the top of the band 2 to within a fraction of an inch of the bottom of the tank 1. It is secured in sealing relation to the band 7 by an outwardly extending flange 17, which flange in turn, at its extreme outer edge, is bent upwardly to constitute a rim 18 which fits against the inner surface of the band 7 and is secured thereto, as by welding. At its lateral edges, the wall member 16 is also provided with outwardly extending flanges 19 (see Fig. 4) which fit relatively close against the inner surface of the tank 1 when the collar 2 is positioned thereon. The wall member 16 defines with the juxtaposed portion of the wall of tank 1 and the band 7 an air chamber extending from the level of the oil in the tank 1 up to the flange 17. This air chamber really functions as an air passage for transmitting air from the exterior into the tank 1 above the level of the oil therein. Thus, the wall member 16 is provided with a plurality of vertical slots 20 extending substantially the full length of the member 16 for supplying air through the wall member 16, and the band 7 is provided with apertures 21 for admitting air from the exterior into the space or chamber defined by the wall member 16. The amount of air entering the apertures 21 may be controlled by a slide 22 mounted in guides 23 and having apertures 24 therein adapted to be moved into or out of registration with the apertures 21 by moving the slide circumferentially on the collar. The apertures 21 may be approximately 1" in diameter and there may be three of them on a heater of average size. The slots 20 may be approximately $\frac{1}{8}$ " wide and spaced about $1\frac{1}{2}$ " apart. The spacing between the wall of the tank and the wall member 16 may be about $1\frac{1}{4}$ ". The wall member 16 may extend circumferentially about one-third the way around the tank.

It is found that with the structure disclosed, unusually complete combustion is produced, probably by reason of the fact that the air is pre-heated, to a certain extent, within the recess or chamber defined by the wall 16 and is then

discharged in relatively small jets through the slits 20 to mix intimately with the gas burning in the tank. Of course, as the burning gas ascends into the stack 4, it is mixed with additional air discharged through the apertures 15 in the head 14 prior to being discharged into the stack. The apertures 15 may be approximately $\frac{1}{16}$ " in diameter and the discharge head 14 may be approximately $3\frac{1}{2}$ " in diameter and contain in the neighborhood of 90 apertures, all told. This number, of course, may be varied by experiment to determine the optimum number and size for most complete combustion with any particular fuel and a tank of any particular dimensions.

The stack 4 is preferably constructed in two sections, the lower section comprising a straight tubular member 25 which fits over the flange 8 on the cover 3 and is tapered inwardly slightly at its upper end, like the reduced end of a stove pipe, to fit within and support an upper stack section 26 which is tapered gradually to a reduced diameter at the upper end. The lower stack section 25 is provided with a plurality of flanges 27 extending circumferentially thereabout at spaced intervals and the upper stack section 26 is similarly provided with a plurality of circumferentially spaced flanges 28. Both flanges 27 and 28 perform the function of radiating heat from the stack sections on which they are mounted, to surrounding objects. We have also found it desirable to provide in the lower stack section 25 a plurality of air inlet apertures 29, there being a row of these apertures 29 below each of the flanges 27. The draft through the stack is sufficient to draw in air through the apertures 29. The upper stack section 26 is also provided with apertures 30, these apertures being positioned below the flanges 28. The apertures 30, however, are preferably substantially larger and fewer in number than the apertures 29 and function as discharge passages for burning gases and products of combustion. This is by virtue of the fact that the stack 26 is tapered to a reduced diameter at the top. A substantial portion of the burning gases are discharged through the apertures 30 against the under sides of the flanges 28, thereby further heating those flanges and causing them to radiate heat to surrounding objects. In normal operation, there will be a small amount of flame issuing from each of the apertures 30, as well as from the upper end of the stack section 26. To facilitate the discharge of flame and burning gases through the discharge apertures 30, an inwardly and downwardly extending baffle 31 is preferably provided immediately above each of the apertures 30, this construction being fully disclosed and claimed in the co-pending Nance application previously referred to.

As previously indicated, one of the chief advantages of the present invention is that by the use of the band 2, as described, existing tanks 1 and covers 3 may be utilized to produce a more efficient and substantially smokeless heater, it being only necessary for an orchardist owning old type heaters to purchase the bands 2 and the stacks 4 in order to modernize his equipment.

The equipment so far described relates to burners employing circular or cylindrical type tanks. However, at present there are a great many orchard heaters in use which have tanks which are square in horizontal section instead of round. The tanks also usually have side walls which are flared upwardly and outwardly. Of course, it is obvious that a band employing air

inlet apertures as described in connection with Figs. 1 to 5, may be made in square shape to adapt square pots or tanks of existing design. However, we have discovered that it is more difficult to provide a tight connection between the auxiliary band and a square top tank than on a round top tank. The chief reason for this seems to be that the flat sides of the square tanks are more apt to be bent so that it is difficult to fit a band to them when the band merely sets on the upper edge. We have also found that it is quite important that the band fit snugly on the tank and prevent any great amount of air leakage at that point else the operation of the burner is seriously interfered with. We have found that it is feasible, however, to construct a band that will fit snugly on square tanks by employing the construction shown in Figs. 6, 7 and 8. Thus, referring to Fig. 6, the usual square type tank 51 is provided with a rolled or beaded upper edge 51a, usually formed by wrapping the upper edge of the tank about a rod or wire. The usual cover 53a for a square tank sets directly on top of the beaded or rolled edge 51a. However, as previously indicated, if a tank has been badly bent, it is often impossible to secure a tight connection between a cover or a band and the tank by merely employing a surface on the cover or band adapted to set on top of the head 51a. To this end we preferably form a band 32 for a square tank with inwardly and downwardly extending skirt members 33. Thus, the band 32 may be formed of sheet metal bent outwardly and back on itself to form a seat 34 adapted to rest upon the bead 51a of the tank and then extend the material on down past the seat 34 to form the skirts 33. These skirts 33 extend straight downwardly from the band 32 prior to attachment of the band to the tank. However, the corners of the skirts 33 are cut away, as indicated at 35 in Fig. 7, so that as the band 32 is pressed down onto the tank, the skirts 33 slide along the inner surface of the walls of the straight tank and are bent inwardly, thereby to form a tight fit against the walls of the tank. As a result of this inward bending of the skirt members 33, the corners of the skirts come together substantially as shown in Fig. 8.

Aside from the details mentioned, the construction of the band for a square tank is substantially the same as that for a round tank. Thus, it employs an air inlet head 37 having apertures 38 therein, the head being connected to the exterior and mechanically supported by tubes 39 extending to diametrically opposite points on the band. Likewise, an inner wall member 40 is provided having slots 41 for supplying air to the tank, the flow of the air being controlled through ports 43 in the band by means of a slot 44 having apertures therein. Of course, whereas in the round tank, the false wall extended circumferentially for a portion of the way about the cylindrical wall of the tank, the wall 40 for a square tank would be straight and extend down along only one side of the square tank.

Referring to Fig. 2, it will be observed that oil will be maintained at the same level on both sides of the wall 16 and a certain amount of combustion may take place in the space above the oil between wall 16 and the adjacent wall of the tank. However, because of the small area of the oil surface exposed in this space, most of the air will pass from the apertures 21 through the slots 20 without being consumed and the main vapor generation and combustion takes place beyond the wall 16. Improved operation re-

sults from the fact that air is introduced through the slots 20 substantially at the oil surface, regardless of the height of the oil level in the tank. It is to be understood that although the air inlet apertures 20 have been disclosed as vertical slots, they need not necessarily be in this form, and if desired, numerous small holes distributed over the wall may be employed instead of the vertical slots.

10 As previously indicated, the invention has been explained by describing in detail certain specific embodiments thereof, it being understood that various changes can be made from the particular structure shown without departing from the invention which is to be defined as set forth in the appended claims.

We claim:

1. An orchard heater of the type described for burning oil, a receptacle for containing oil, said receptacle having an open top, a collar detachably mounted on said receptacle, a cover detachably mounted on said collar and having a discharge aperture therein for a stack, and a stack mounted on and extending upwardly from said cover, said collar incorporating means for supplying air for combustion into the space defined by said receptacle, collar, and cover, the upper edge of said receptacle and the lower edge of said cover being so shaped and dimensioned as to be detachably connectible directly together whereby the heater may be used either with or without said collar.

2. In an orchard heater of the type described for burning oil, a receptacle for containing oil, said receptacle having an open top, a collar detachably mounted on said receptacle, a cover detachably mounted on said collar and having a discharge aperture therein for a stack, and a stack mounted on and extending upwardly from said cover with a wall member attached to and supported by said collar cooperating with a portion of the wall of said receptacle to define an air inlet passage, said collar having openings therein for admitting air into said inlet passage and said wall member having numerous small openings therein for admitting air from said passage to said receptacle, the upper edge of said receptacle and the lower edge of said cover being so shaped and dimensioned as to be detachably connectible directly together whereby the heater may be used either with or without said collar.

3. A heater as described in claim 2 in which said wall member extends substantially to the bottom of said receptacle and said openings in said wall member are distributed substantially over the full vertical dimension of said wall member.

4. In a heater of the type described comprising in combination a receptacle for containing oil and generating vapor therefrom and a stack for the combustion of oil vapor generated in said receptacle; the stack construction comprising a first vertical tubular member of substantially uniform dimensions from top to bottom, the lower end of said first section fitting to said receptacle, one or more annular flanges secured to and extending outwardly from said first section, said section having a plurality of air inlet apertures therein immediately below said annular flanges, and a second stack section fitting on top of said first stack section, said second section being tapered from a large diameter at the bottom to a small diameter at the top and being open at the top, a plurality of annular flanges secured

to and extending outwardly from said second section, and a plurality of discharge apertures in said second section positioned immediately below the flanges thereon.

5. A fuel-combusting, draft-inducing and heat-radiating stack for an orchard heater comprising a first vertical tubular member of substantially uniform dimension from top to bottom and open at both ends, the lower end being adapted to receive incompletely burned gases, one or more annular flanges secured to and extending outwardly from said first section, said section hav-

ing a plurality of air inlet apertures therein immediately below said annular flange, and a second stack section fitting on top of said first stack section, said second section being tapered from a large diameter at the bottom to a small diameter at the top, and being open at the top, a plurality of annular flanges secured to and extending outwardly from said second section, and a plurality of discharge apertures in said second section positioned immediately below the flanges thereon.
